JOHN B. BOLITHO, OF ELTHAM, ENGLAND.

AMPLIFYING DEVICE FOR USE IN WIRELESS TELEGRAPHY.

1,407,245.

Specification of Letters Patent. Patented Feb. 21, 1922.

Application filed September 18, 1920. Serial No. 411,104.

To all whom it may concern:

Be it known that I, JOHN BRUCE BOLITHO, a subject of the King of Great Britain, and residing at Eltham, in the county of Kent, 5 England, have invented certain new and useful Improvements in Amplifying Devices for Use in Wireless Telegraphy, of which the following is a specification.

This invention relates to amplifying arrangements used in wireless telegraphy. Such amplifying arrangements are also applicable for use as relays. The principle on which the invention is based will be understood from the accompanying diagram.

15 Let us assume that the plate 1 of a three-electrode valve is connected in a circuit containing reactance 4, a high voltage battery 6, an indicating or recording device or relay 7, and say a milli-ammeter 8 to the filament 3; 6, 7 and 8 are shunted by a capacity 5 of suitable size in order to provide a low resistance path for oscillating currents. The grid 2 is connected through a tuned reactance 9 (coupled in the normal way with 20 reactance 4 in the plate circuit), a suitable number of cells 10 and a potentiometer 11 to the filament 3. These cells 10 and the potentiometer 11 are used to control the potential of the grid 2 relatively to the filament 25 3. If these cells were removed the circuit would start oscillating and would maintain oscillations on its own account, but if the negative potential on the grid 2 were increased it would be found that there was a 30 point at which the circuit would not sustain and amplify very small oscillations. This point is a critical one. By the present invention, the voltage is arranged so that the valve and its accompanying circuits are 35 unable to build up and sustain any very small oscillations.

Now let us suppose that the potential of the grid is arranged to be say 0.1 volt less than the critical point referred to above, at 45 which the valve may be said to be unable to initiate oscillations. Then, if incoming signals are applied to the grid circuit so that the potential of the grid of the valve is caused to oscillate, when the oscillations 50 cause the grid to be raised to a potential of the critical value or greater, oscillations will build up rapidly in the anode and grid circuits, and will be sustained until quenched by some external agency. As soon as the 55 valve starts to "oscillate," due to impulses received for instance from coil 33 in a signal

circuit inductively coupled with coil 9, the anode current between 3 and 1 becomes very much greater than before, thus giving the required amplification. The use of this 60 principle combined with a method of rapid quenching is the basis of the present invention.

The method of quenching the oscillations according to this invention is an electrical 65 one. A second valve is provided with its filament 14 connected in parallel through leads 16, 17, to the terminals of battery 15 and filament 3 of the first valve, while the grids of the two valves are joined with or without arrangements to apply a different potential to the second as compared with the first. In the arrangement shown, grid 2 of the first valve is connected to grid 13 of the quenching valve through lead 18, and a 70 variable battery 19 in parallel with a shunt capacity 20. The plate 12 of the second valve is joined to its filament 14 through lead 21, a reactance 22 and a source of alternating current 23 of a frequency which will generally be much less than that of the incoming signal. The reactance coil 22 in this plate circuit, which we may term the "quenching circuit," is coupled to the coil 9 connected to the grid 2 of the amplifying circuit, but with its reactance reversed. Other details indicated in the diagram of connections of the two valves are a tuning condenser 34 in parallel with coil 9, a shunt capacity 35 in parallel with battery 10, a voltmeter 36 between battery 10 and the filament 3, and a milli-ammeter 37 in the circuit of the high tension supply 23 leading to filament 14. 75 80 85

Now it will be seen that when the potential of the plate 12 of the quenching circuit becomes sufficiently positive, the reactances of the two plate circuits will balance out as the reactance of coil 22 is reversed, i. e. tending to damp out oscillations, so that the oscillations in circuit 9, 34, will be quenched. 90 Again, if the plate 12 of the quenching circuit is brought to a higher positive potential, the resultant of the two reactances will be a reversed reactance, and the oscillations will be quenched even more rapidly. When the potential of the plate 12 of the quenching circuit is negative, the quenching circuit becomes inoperative and the amplifying circuit is able to be "triggered" (set in oscillation) 95 and the oscillations will persist with much increased anode current until the resultant reactance again becomes small enough or 100 105 110

strongly enough reversed to damp out the oscillations. It will be seen that the reactance of the amplifying circuit is varied according to the modulations which are imposed for quenching purposes. The action really amounts to varying intermittently the oscillation resistance by electrical means, with the use of a valve, which serves to damp out periodically the oscillations produced by a "triggered" valve.

The source of high tension A. C. supply 23, is shown as consisting of a coil 24 connected across the terminals of a capacity 25 between coil 22, and filament 14 in the quenching circuit, while coil 24 is coupled inductively with coils 26, 27, in a valve circuit for generating oscillations. Of the coils, 26 is connected between the grid 30 and cathode 31 of the valve, whose plate 29 is connected to the + terminal of a high voltage supply 32, while coil 27 is connected in parallel with capacity 28 between filament 31 and the - terminal of the high voltage supply 32. In place of the arrangement last above described, any source of electrical oscillations or impulses may be used which will make the plate 12 intermittently and sufficiently positive to bring the reversed reactance between the coils 9 and 22 into operation, so as to produce a quenching action.

The signals may be applied to the valve circuit in any suitable manner, so that when signals are received the valve will be "triggered" owing to the slight changes in voltage on the grid 2.

Having now particularly described and ascertained the nature of my said invention and in what manner the same is to be performed, I declare that what I claim is:—

1. An amplifying arrangement for use in wireless telegraphy, wherein automatic electrical means are employed for damping out periodically the oscillations produced in a circuit by a "triggered" amplifying valve, such automatic electrical means of damping comprising a valve varying intermittently the oscillation resistance of the circuit of the "triggered" amplifying valve.

2. An amplifying arrangement for use in wireless telegraphy comprising a plurality of three electrode valves, a reactance in the plate and filament circuit of each of said valves, said reactances being coupled together but acting in opposite directions, the filaments and grids of the said valves being connected together in parallel respectively, a reactance in the grid circuits, a receiving circuit with a reactance, all the said reactances being coupled together and means for supplying a high tension alternating current to the plate and filament circuit of one of the valves.

3. An amplifying arrangement for use in wireless telegraphy comprising a plurality

of three electrode valves with the necessary circuits therefor, reactances in the filament and plate circuits and in the grid circuit of said valves, said reactances being coupled together, a receiving circuit with a reactance coupled to the reactances of the said three electrode valves and means for supplying a high tension alternating current of low frequency to one of said valves, the reactance of said valve being arranged in the reversed direction to the reactance of another of said valves so that the oscillations of the last mentioned valve will be quenched as rapidly as is required according to the frequency of the oscillations applied to the other valve inductively coupled therewith.

4. An amplifying arrangement for use in wireless telegraphy comprising a three electrode valve, a reactance in circuit with the plate and filament circuit of said valve, a tuned reactance in circuit with the grid of said valve, means for adjusting the potential of the grid relatively to the filament, a receiving circuit with reactance, the three reactances being coupled together, a second three electrode valve, the filament and grid of said second valve being connected in parallel with the filament and grid of the first valve, a reactance in the plate and filament circuit of the second valve, said reactance being coupled to the reactance of the plate and filament circuit of the first valve but arranged in a reversed direction and means for supplying a high tension alternating current to the plate and filament circuit of the second valve.

5. An amplifying arrangement for use in wireless telegraphy comprising a three electrode valve, a reactance, battery and recording means in circuit with the plate and filament of said valve, a capacity in shunt with the battery and recording means, a tuned reactance in the grid circuit of said valve and coupled to the first reactance, a potentiometer for adjusting the potential of the grid relatively to the filament, a receiving circuit with reactance, a second three electrode valve, the filament and grid of the second valve being connected in parallel to the filament and grid respectively of the first valve, a reactance in the plate and filament circuit of the second valve, said reactance acting in the opposite direction to the reactance in the plate and filament circuit of the first valve, all said reactances being coupled together, and means for supplying a high tension alternating current to the plate and filament circuit of the second valve.

6. An amplifying arrangement for use in wireless telegraphy comprising a three electrode valve, a reactance, battery and recording means in circuit with the plate and filament of said valve, a capacity in shunt with the battery and recording means, a tuned reactance in the grid circuit of said valve

- and coupled to the first reactance, a potentiometer for adjusting the potential of the grid relatively to the filament, a receiving circuit with a reactance, a second three electrode valve, the filament and grid of the second valve being connected in parallel to the filament and grid respectively of the first valve, means for applying a different potential to the grid circuit of the second valve 5 as compared with the grid circuit of the first valve, a reactance in the plate and filament circuit of the second valve, said reactance acting in the opposite direction to the reactance in the plate and filament circuit 10 of the first valve, all said reactances being coupled together and means for supplying a high tension alternating current to the plate and filament circuit of the second valve.
7. An amplifying arrangement for use in 15 wireless telegraphy comprising a three electrode valve, a reactance, battery and recording means in circuit with the plate and filament of said valve, a capacity in shunt with the battery and recording means, a tuned reactance in the grid circuit of said 20 valve and coupled to the first reactance, a potentiometer for adjusting the potential of the grid relatively to the filament, a receiving circuit with a reactance, a second three electrode valve, the filament and grid 25 of the second valve being connected in parallel to the filament and grid respectively of the first valve, a reactance in the plate and filament circuit of the second valve, said reactance acting in the opposite direction to the reactance in the plate and filament circuit 30 of the first valve, all said reactances being coupled together, a second reactance and capacity in parallel in the plate and filament circuit of the second valve, a third 35 three electrode valve, means for inductively coupling the circuit of said third three electrode valve with the second reactance in the circuit of the second three electrode valve, and means for connecting said third three 40 electrode valve to a high voltage supply.
